UNITED STATES PATENT OFFICE.

SAMUEL S. FERTIG, OF TITUSVILLE, PENNSYLVANIA.

EJECTOR.

SPECIFICATION forming part of Letters Patent No. 309,214, dated December 16, 1884.

Application filed March 13, 1884. (No model.)

To all whom it may concern:

Be it known that I, SAMUEL S. FERTIG, a citizen of the United States, residing at Titusville, in the county of Crawford and State of Pennsylvania, have invented a new and Improved Auxiliary Ejector for Oil or Artesian Wells, of which the following is a specification.

My invention relates, principally, to flowing-wells or wells that are made to flow by confining the natural gas coming from the well, causing it to exert its pressure upon the surface of the oil and raising it through the tubing to the surface. My object is to assist this natural flow by artificial means by inserting in the tubing of the well, at some proper point between the gas-packing ring and the mouth of the well, an ejector, through which gas, steam, or compressed air shall be injected into the tubing, assisting the gas in the well itself in raising the column of fluid. I accomplish this by the device illustrated in the accompanying drawings, in which—

Figure 1 represents a broken vertical section of a well showing the well-mouth, the ejector, the gas-packing ring, and the bottom of the well. Fig. 2 represents the ejector drawn on a larger scale; Fig. 3, a horizontal section on line $\alpha\alpha$ in Fig. 2, and Fig. 4 a bottom view of the valve-ring in the ejector.

Similar letters in the several views refer to the same parts.

A represents the walls of the well; B, surface of ground; C, the bottom of the well; D, gas-bearing rock; E, oil-producing rock. These may be, and frequently are, one and the same.

F is the casing resting on the shoulder G in the walls of the well, forming there a tight joint, through which no fluid can escape.

H is the tubing, extending from above the surface to the bottom of the well. This is perforated at and near the bottom, as shown, to admit the oil.

I is the lead pipe from the tubing to the tanks.

K is the packing-ring placed round the tubing above the gas-bearing rock D, filling the space between the tubing and the wall A of the well, and preventing the escape of gas up and around the tubing.

So far as described the well is drilled, tubed,

and packed in the ordinary manner for flowing-wells. The gas, being confined by the packing-ring K, exerts a pressure upon the surface of the oil around the tubing and forces it in through the perforations at the bottom and up to the surface. To assist this flow, I place in the tubing, at some point above the packing-ring K and below the well-mouth, the ejector L, constructed as shown more clearly in Fig. 2. At the lower end of the ejector, where it is attached to the tubing, it is of the same diameter as the tubing, but above that point is reduced or contracted, in a cone shape or reducer M, to one-half the diameter, or less, as required, the upper end of the cone being open into the upper part of the tubing H. Around this cone, at a proper point, is placed the shoulder N, and on the shoulder the collar O, to which is attached the tubing H above. Between the cone M and the collar O is left a conico-cylindrical space, and in this space is placed the ring P, fitted to play loosely up and down inside the collar O, and with its inner surface beveled to correspond with the outer surface of the cone M, and so that when it rests on the shoulder N it entirely fills the space between the cone M and the collar O.

Through the shoulder N are the holes or perforations R, of any desired size and number, forming a fluid-connection between the chamber outside the tubing and the inside, except when closed by the ring P, resting on the shoulder N, the ring P acting as a valve, and the shoulder N as the valve-seat. When the ring-valve P is raised by the pressure of fluid from the outside, it leaves a space between the inside of the valve-ring and the cone M, through which the fluid entering through the perforations R passes up into the tubing H. The ring-valve P is prevented from rising too far by coming in contact with the lower end of the tubing H.

S is a pipe entering the casing-head and into the chamber surrounding the tubing H above the gas-packing ring K.

The operation is as follows: The well being tubed in the ordinary manner, and with the ejector L placed in the tubing at some point where desired between the gas-packing ring K and the mouth of the well, the well flows in the ordinary manner till the oil is raised in the tubing H above the ejector L, the valve-

ring P being held closed by its own weight and the weight of the superincumbent fluid. If it is now desired to assist the natural flow of the well, a current of steam, air, or gas is forced 5 in through the pipe S to the chamber outside the tubing H until the pressure is sufficient to overcome the weight of the superincumbent fluid upon the valve-ring P, when the valve-ring is raised and the compressed fluid flows 10 upward around the cone M into the tubing H, acting as an ejector, assisting the flow of oil and carrying the oil from the point of the cone M to the mouth of the well. Whenever 15 the pressure ceases or lessens through the pipe S, the valve-ring P closes of its own action. The fluid introduced through the pipe S may be steam from a boiler, air from a compressor, or natural gas from some contiguous well, as may be most convenient.

20 I make no claim for the broad principle of an ejector as a device for raising fluid from an Artesian well, as that is an old device, although never, to my knowledge, having been applied to assist the natural forces.

25 What I do claim as my invention is—

1. In an oil or Artesian well, an ejector in-

serted in the tubing at some point above the gas-packing ring and below the well-mouth, to supplement the natural forces of the well in ejecting the fluid therefrom, substantially 30 as described.

2. In an oil or Artesian well, the auxiliary ejector L, inserted in the tubing above the gas-packing ring K and below the well-mouth, said ejector constructed with the cone M, 35 shoulder N, with perforations R, collar O, and valve-ring P, all constructed and operating substantially as shown and described.

3. The ejector L, inserted in the tubing of an oil or Artesian well at some point between 40 the gas-packing ring K and the well-mouth, and operated by compressed air, steam, or gas introduced into the chamber surrounding the tubing and ejector as a device for supplementing the natural forces in ejecting the 45 fluid from the well, substantially as shown and described.

SAMUEL S. FERTIG.
